HAND-THREADING SHUTTLE.

1,156,034.

Specification of Letters Patent.

Patented Oct. 5, 1915.

Application filed January 2, 1913. Serial No. 739,832.

To all whom it may concern:

Be it known that I, RICHARD PACKER, a citizen of the United States, and a resident of Fall River, in the county of Bristol and State of Massachusetts, have invented an Improvement in Hand-Threading Shuttles, of which the following description, in connection with the accompanying drawings, is a specification, like characters on the drawings representing like parts.

This invention relates to hand threading shuttles, primarily, the purpose thereof being to produce a shuttle that may be easily threaded by hand, and from the threading aperture of which the thread cannot be accidentally displaced.

In order that the principle of the invention may be readily understood, I have disclosed a single embodiment thereof in the accompanying drawings, wherein—

Figure 1 is a plan view of the forward portion of a loom shuttle embodying my invention, a portion thereof being shown in transverse section; Fig. 2 is a side elevation of the structure shown in Fig. 1; Fig. 3 is a vertical transverse section taken through the shuttle upon the line 3—3 of Fig. 1; Fig. 4 is a front elevation of the threading member; Fig. 5 is a side elevation thereof, the member being slightly tilted; and Fig. 6 is a transverse section thereof on an enlarged scale.

The invention, in certain aspects thereof, may be applied to shuttles not of the hand threading type.

Referring to the drawing, the body of the shuttle is represented at 1, it being of any usual or suitable character, shape and material. Mounted therein in any suitable manner is a weft carrier, here shown as a bobbin 2, which may be mounted on the usual spindle, not shown. Upon the bobbin is positioned the usual weft package 3. Axially in advance of the bobbin is the usual recess 4 which leads to the transverse socket 5, wherein the threading member is adapted to be positioned. The said transverse socket penetrates from the side surface of the shuttle transversely to a point of intersection with the recess 4. The shuttle body 1 is suitably slotted in order to permit the thread to be passed manually into and through the socket 5, thus avoiding the sucking of the thread through by the op-

erative. For this purpose, I have represented an arcuate slot 6 cut or otherwise suitably formed in the top surface of the shuttle and a longitudinal slot 7 communicating with the slot 6 in the usual or any desired manner. The arcuate slot 6 communicates at its inner end with the recess 4 at the front thereof preferably on the side the more remote from the side of the shuttle through which the thread 8 issues.

The parts thus far described may be of any suitable construction. Within the transverse socket 5 is positioned a threading member which, in this embodiment of the invention, is shown as a plate 9 preferably of soft steel. This plate is adapted to be secured within the socket 5 by a screw or other holding means penetrating the top of the shuttle above said socket. To this end, the said plate may be provided with a suitable hole for the reception of the screw or the plate may be fitted tightly into position in the socket and held thereby by friction, but in such a manner as to permit it to be withdrawn when desired. The threading member 9, which for simplicity of construction is preferably made in a single piece, is so constructed that it imparts the desired friction to the thread in the weaving operation in both directions of throw of the shuttle. Furthermore the construction of said threading member is such that the thread is at all times positively held in proper, predetermined position, not only so that the shuttle cannot be unthreaded, but so that the thread is held in that position where the required tension is necessarily applied thereto.

The plate 9, as shown most clearly in Figs. 2 to 6 inclusive, is provided with a projecting prong 10 preferably integral therewith and reversely bent into general loop form, the end 11 thereof extending into close proximity to or into a socket or recess 12 formed in the plate. The prong 10 is preferably located close to or at that side of the plate which is nearest the side wall 12' of the shuttle. Inasmuch as the plate is preferably of soft steel, it is possible to bend the prong into the desired shape and to vary the shape thereof or the position of the extremity 11 of the prong as desired.

Adjacent its opposite extremity the plate 9 is provided with an eye 13 which is axially in line with the spindle on which the bobbin

2 is mounted, so that the thread 8 is delivered axially of the bobbin into said eye 13. To permit the proper threading of the shuttle, the eye 13 is provided with a flaring or 5 other opening 14, and if desired the upper surface of the plate may be slightly recessed in the rear of the eye 13 for the thread 8.

The thread receives friction as it passes along the upper surface of the plate to the 10 eye 13. It will be observed that one wall of the opening 14 is bent upwardly. This insures the passage of the thread below that part of the plate which is between the eye 13 and the adjacent prong and guides 15 the thread into its proper position with respect to the said prong. This purpose is readily accomplished by slightly twisting that portion of the metal which is between the opening 14 and the said prong.

20 Between the eye 13 and the looped prong 10, there is provided a second prong 15 preferably struck down from the body of the plate 9, as indicated most clearly in Fig. 1. This prong 15 is preferably curved rearwardly, as represented, so as to provide a slightly concaved, localized, guiding portion 16 for the thread. Inasmuch as the plate is made of soft steel, it is possible to bend the prong 15 so as to bring it in correct 25 position with reference to the portion 17 of the prong 10 to impart the desired tension to the thread, and hence to vary the position of the prong 15, depending upon the character of thread and the amount of tension required thereby, it being the purpose 30 of the construction to provide a somewhat circuitous route for the thread about the two prongs 15, 10, so that friction is applied to the thread both by the prong 15 and by 35 the prong 10. If desired, the prong 15 may be structurally distinct from the plate 9 and applied thereto in an adjustable manner, so as to permit it to be positively adjusted in and out with respect to the front prong 10, 40 thereby to secure the proper friction, and to vary the friction with the character of the thread. It will be observed that in the construction shown the prong 15 is substantially 45 in transverse alinement with the portion 17 of the prong 10, thus compelling the thread to take a circuitous route to the front of the prong 15 and to the rear of the part 17 of the prong 10.

50 The thread 8 is drawn into the arcuate slot 55 6 down into the slot 7 and is then drawn past the extremity 11 of the prong 10 or to the left thereof viewing Figs. 2 and 6. The relation of the extremity 11 of the prong 10 to the socket or recess 12 is such that the 60 thread is in the threading operation passed up into the socket or recess 12 about the point 11 and thence down into the looped portion of the prong 10. The construction is such that it is impossible to reverse the 65 operation and dethread the shuttle by pass-

ing the thread up past the point 11 into the recess 12, and thence to the right, viewing Fig. 6.

When the shuttle is moving toward the right, viewing Figs. 1 and 2, the thread 70 receives friction against the front face of the prong 15 and also against the inner face of the member 17 of the prong 10, thus imparting the desired friction, and when the shuttle is moving in the opposite direction or 75 to the left viewing Figs. 1 and 2, the thread receives friction against the outer face of the prong 15 and against the opposite member of the prong 10.

It will be observed that the curved formation of the prong 15 and of the member 17 of the prong 10 are such that the thread is fixedly held from vertical movement along these prongs and hence cannot be moved upwardly toward the end 11 of the looped 80 prong 10. The spacing apart of the prongs 10 and 15 is important, for if they were continuous there would be but little friction imparted to the thread which would slide freely along them, but by providing the 85 separated prongs or projections as described, there is sufficient friction imparted to prevent the too free playing off of the thread from the shuttle.

Obviously the entire structure can be 90 stamped from a single piece of metal and bent into shape at a single operation and at exceedingly slight cost.

The construction is such as absolutely to 95 prevent the dethreading of the shuttle, while at the same time sufficient friction is imparted to the thread whatever the direction 100 of motion of the shuttle.

Having thus described one illustrative embodiment of my invention, I desire it to be 105 understood that although specific terms are employed, they are used in a generic and descriptive sense and not for purposes of limitation, the scope of the invention being set forth in the following claims.

1. A hand threading shuttle provided with a transverse threading socket, a threading member positioned therein and consisting of a plate portion having an eye 13 and a plurality of prongs extending from one face thereof in substantial transverse alinement with said eye, one of said prongs being bent into loop form and surrounding the thread, and another of said prongs being positioned so as frictionally to engage the thread passing through said loop.

2. A hand threading shuttle provided with a transverse threading socket, a threading member positioned therein and consisting of a plate portion having an eye leading to the under face thereof and a plurality of prongs extending from said under face thereof and in substantial transverse alinement, one of said prongs being bent into loop form and surrounding the thread, and another of said 130

- prongs extending in substantial parallelism to a portion of said looped prong.
3. A hand threading shuttle provided with a transverse threading socket, a threading plate positioned therein and having spaced prongs, one of which is bent into looped form, and having an eye extending through the plate for the passage of the thread directly to said prongs, the latter being relatively positioned to compel friction of the thread against both prongs in either direction of throw of the shuttle.
4. A threading member for a hand threading or other shuttle consisting of a plate adapted to be inserted in a threading socket of the shuttle and having a plurality of spaced prongs extending from one face thereof, one of said prongs being reversely bent into loop form, a plurality of said prongs being oppositely concaved to provide a limited path for the thread.
5. A hand threading shuttle provided with a transverse threading socket, a threading plate positioned therein and having downwardly extending, spaced projections oppositely curved to provide a localized, predetermined thread path, one of the prongs being bent into loop form and having an extremity extending into close proximity to the under surface of the plate, thereby to prevent dethreading.
6. A hand threading shuttle provided with a transverse threading socket and intersecting threading grooves, a metal threading plate positioned in said socket and having an eye and entering recess in axial alignment with the axis of the bobbin and two downwardly extending, thread positioning and tension creating prongs, one of said prongs being bent into loop form, the two

members of which alternately coöperate with the other prong to impart friction to the shuttle in opposite directions of throw.

7. A hand threading shuttle provided with a transverse threading socket, a threading member positioned therein and consisting of a plate portion and a plurality of prongs extending from one face thereof, one of said prongs being bent into loop form and surrounding the thread adjacent the thread exit from the shuttle, and another of said prongs being in substantial transverse alinement with a portion of said looped prong, but positioned to compel a somewhat circuitous route for the thread past said prongs, said plate portion having a guiding eye in longitudinal alinement with the axis of the weft package and extending through the plate from face to face thereof.

8. A hand threading shuttle provided with a transverse threading socket, a threading member positioned therein and consisting of a plate portion having an eye leading to the under face thereof and a plurality of prongs extending from said under face and in substantially transverse alinement, one of said prongs being bent into loop form and surrounding the thread, and another of said prongs extending in substantial parallelism to a portion of said looped prong, said prongs being positioned to compel a somewhat circuitous route for the thread past them.

In testimony whereof, I have signed my name to this specification, in the presence of two subscribing witnesses.

RICHARD PACKER.
